Fig. 3.

Fig. 4.

FIG. 1 is a top plan view of a Christmas tree ornament showing my new design,

FIG. 2 is a front elevational view,

FIG. 3 is a side elevational view, and

FIG. 4 is a bottom plan view thereof.

The characteristic features of my design reside in the combination of the two opposite faces on the Christmas tree ornament disclosed each having an apex below the center of the ornament and a girdle around each face, together with elongated facets at the upper portion and shorter facets at the lower portion thereof, said facets emanating from each of the apices and respectively extending therefrom to the girdles all as shown.

I claim:

The ornamental design for a Christmas tree ornament or similar article, substantially as shown and described.
